REAMER AND HONER FOR WRIST PIN
BUSHINGS

Cecil L. Clark, Three Rivers, Calif.

Application July 29, 1947, Serial No. 764,333

3 Claims. (Cl. 77—75.5)

1

This invention relates to an adjustable reamer and honer for the bushing of wrist pins.

The connecting rod of an internal combustion engine is pivotally fastened to its piston by a wrist pin. The end of the connecting rod is fitted with a bronze bushing, and the central portion of the wrist pin passes through the bushing. The ends of the wrist pin are accommodated in drilled holes in the skirt of the piston. The wrist pin may be anchored to either the piston or the connecting rod so as to be free to turn with respect to the other, or may be full floating to turn freely with respect to both.

It is, of course, essential that the wrist pin fit accurately with respect to the bushing. When a bushing is first reamed, it contains numerous hair lines or high spots, and the fitting of the wrist pin in the bushing is based on these hair lines. Consequently, when the pin is inserted in its bushing, it engages only the hair line. The maximum bearing surface for the pin under such conditions does not ordinarily exceed a fraction of the entire bearing surface of the bushing. This necessarily results in quick wearing of the bushing, and this causes knocks, rattles, and other objectional conditions which are antagonistic to high efficiency operation of the engine.

It is a principal object of this invention, therefore, to provide a tool for giving the bushing a true and smooth bearing surface. More particularly, this tool is designed to ream and hone the bearing surface of the bushing to result in a smooth and highly polished surface. This tool is operable by a lathe or electric drill, and is furthermore adjustable to provide for different sizes of bushings.

A preferred embodiment of the invention is illustrated in the accompanying drawings, but it is understood that modifications may be made therein without departing from the spirit of the invention as hereinafter claimed.

Figure 1 is a front elevation of the new and improved tool, shown in conjunction with the bushing of a connecting rod, some of the parts being shown in section.

Figure 2 is another front elevation of the tool, some of the parts thereof being shown in section.

Figure 3 is transverse vertical section, on an enlarged scale, taken through the line 3—3 of Figure 1.

Figure 4 is a side elevation of a device for adjusting the tool.

Figure 5 is a front elevation of another adjusting means.

2

Figure 6 is a front elevation of an adapter for driving the tool from the chuck of the lathe or drill press.

Figure 7 is an enlarged transverse section of the tool when an abrasive cloth is used therewith for honing purposes.

Figure 8 is a perspective view of the abrasive cloth.

The device comprises a cylindrical body 10 provided with several pairs of slots 11. These slots 11 are radial, and extend longitudinally of the body 10. A central portion 12 of the body 10 divides the slots 11 into pairs. Four such pairs are shown, but it is obvious that more or fewer may be employed. Each of the slots 11 is adapted to contain a vane 15, that is movable radially of the body 10, for a purpose to be described more particularly hereinafter.

Each of the vanes 15 is provided with two notches 16 on its outer surface, adjoining its end, and an annular coil spring 18 encircles all the vanes 15 at the notches 16 and keeps the vanes 15 in place on the body 10.

The central portion 12 of the body 10 has a plurality of angular cam surfaces 20, one such surface being provided for each of the vanes 15, and the inner ends of the vanes 15 are formed to complement the angular surfaces 20. Consequently, as the vanes 15 are pushed inwardly toward the central portion 12, the adjacent ends of the vanes 15 will ride upwardly on the cam surfaces 20. A similar cam surface 21 is provided on a portion of the body 10 adjacent the outer ends of the vanes 15, and the vanes 15 adjacent thereto are mated. Consequently, translation of the vanes 15 toward the central portion 12 will cause the vanes 15 to ride upwardly on the cam surfaces 20 and 21 in such a way that the vanes 15 remain parallel to the periphery of the body 10.

The outer ends of the body 10 are extended to form sleeves 23 and 24. The inner bore of each of the sleeves 23 and 24 is threaded to receive an adjusting screw 26 and 27, respectively. The inner end of each of the screws 26 and 27 is adapted to bear against the ends of the vanes 15, to produce the axial and radial movement of the vanes 15 with respect to the body 10, hereinbefore mentioned. Each of the adjusting screws 26 and 27 may be provided with a knurled handle 28 and a lock nut 29 to facilitate manipulation of the screws 26 and 27.

The central portion 12 of the body 10 accommodates a radial reamer 31, the reamer 31 being normally urged upwardly by a spring 32 seated in a slot 33 in the central portion 12 of the body

10. The reamer 31 may be locked in position by means of a set screw 35.

Let it be assumed that it is desired to ream the bushing 49 of a connecting rod 41. Let the right-hand vanes 15 of the structure shown in Figures 1 and 2 be called the "leading vanes" and the left-hand vanes be called the "follower vanes." Then the adjusting screw 27 is rotated until the leading vanes 15 can enter the bushing 40 to act as leading guide vanes. The follower guide vanes 15 are then adjusted to indicate the size of the bushing 40 after it has been reamed. To obtain this adjustment, two wrist pins 42 and 43 are mounted between two parallel surfaces 44 and 45, as indicated in Figure 4 of the drawings, 15 a pair of clamps 47 and 48 being one way of insuring parallel relationship between the surfaces 44 and 45 about the wrist pins 42 and 43. The follower end of the body 10 is then inserted between the parallel surfaces 44 and 45, and the 20 adjusting screw 26 manipulated until the follower vanes 15 engage the parallel surfaces 44 and 45, as indicated in Figure 4. In this position, the follower vanes 15 will indicate the correct spacing desired in the bushing 40 to provide the proper fit for the wrist pins 42 and 43. Then, as indicated in Figure 5, a straight edge 49 may be positioned over the follower vane 15, and the 25 reamer 31 adjusted until it is in proper alignment with the follower vanes 15, after which the reamer 31 may be locked in position by means of the set screw 35. Alternately, the reamer 31 and follower vanes 15 may be positioned and adjusted by means of a micrometer.

The sleeve 23 of the body 10 may then be inserted in a chuck 51, which is driven by the shaft 52 of a lathe or drill press, and the sleeve 23 is locked in position in the chuck 51 by means of a locking screw 53. The bushing 40 and connecting rod 41 are slipped over the right-hand end of the body 10, so that the leading vanes 15 may enter the bushing 40. The leading vanes 15 serve as guides, until the bushing 40 contacts the reamer 31. The reamer 31 reams out the interior of the bushing 40, the machined portion of the bushing 40 sliding over the follower vanes 15 on the left-hand portion of the body 10. The springs 18 are in the notches 16 and do not project above the surfaces of the vanes 15.

After the bushing 40 has been reamed, the reamer 31 may be removed, and all the vanes 15 may be replaced by similar blades having a honing surface 60. The bushing 40 may then be positioned over the body 10 until the inner surface thereof has been properly honed by the honing surfaces 60 on the blades 15. If desired, the leading blades 15 may be retained, and only the follower blades 15 be replaced by the honing blades, or the procedure may be reversed.

Proper allowance must be made for the amount of metal removed by the honing process, and for this reason the reamer 31 and the follower vanes 15 may be set initially at a fraction of an inch below the desired diameter, for example, one half of one-thousandth of an inch.

Instead of utilizing blades 15 with a honing surface 60, the follower vanes 15 or both the follower and the leading blades 15 may be removed entirely, and an abrading cloth 65 wrapped around the body 10. The abrading cloth, shown in Figure 8 of the drawings, is provided with a metallic channel 66 along one edge, and this channel 66 is accommodated in a longitudinal slot 67 in the body 10. Or, if desired, the abrasive cloth 65 may be wrapped around the blades

15, as indicated in Figure 7 of the drawings, and the channel 66 tucked into the slot 67 to hold the cloth 65 in position.

To assist the reaming operation, the central portion 12 of the body 10 may be provided with a channel 70 to catch the chips, and the main portion of the body 10 may be provided with another channel 71 extending longitudinally thereof, for a similar purpose.

10. What is claimed is:

1. A reaming tool comprising a cylindrical body, there being at least one pair of radially disposed slots extending longitudinally from each end of said body and terminating at a point spaced from the central part of the latter, a support positioned in the space between said pairs of slots, a reamer mounted within said support transversely of said body for extensible and retractile movement, with respect to the latter, resilient means operatively connected to said reamer for effecting extensible movement of the latter, a vane positioned within each of the slots of one pair and forming a set of leading vanes, another vane positioned within each of the slots of the other pair and forming a set of following vanes, the vanes of each set being mounted for sliding movement radially of said body, and means carried by said body for effecting the radial movement of each set of vanes independently.

2. A reaming tool comprising a cylindrical body, there being at least one pair of radially disposed slots extending longitudinally from each end of said body and terminating at a point spaced from the central part of the latter, a support positioned in the space between said pairs of slots, a reamer mounted within said support transversely of said body for extensible and retractile movement, with respect to the latter, resilient means operatively connected to said reamer for effecting extensible movement of the latter, a vane positioned within each of the slots of one pair and forming a set of leading vanes, another vane positioned within each of the slots of the other pair and forming a set of following vanes, the vanes of each set being mounted for sliding movement radially of said body, and means carried by said body for effecting the radial movement of each set of vanes independently.

3. A reaming tool comprising a cylindrical body,

there being at least one pair of radially disposed slots extending longitudinally from each end of said body and terminating at a point spaced from the central part of the latter, a support positioned in the space between said pairs of slots, said support being provided with two pairs of cam surfaces arranged in opposed relation with respect to each other and in aligned relation with respect to the adjacent ends of said pairs of slots, a reamer positioned transversely of said body and mounted within said support for extensible and retractile movement with respect to the latter, resilient means operatively connected to said reamer for effecting extensible movement of the latter, a vane positioned within each of the slots of one pair and forming a set of leading vanes, another vane positioned within each of the slots of the other pair and forming a set of following vanes, the vanes of each set being mounted for sliding movement longitudinally of the slots of each pair, said vanes having one end bearing against the cam surfaces provided adjacent the ends of said pairs of slots to thereby produce a radial movement with respect to said body upon sliding movement of the vanes of each set longi-

5

tudinally of the slots of each pair, and means bearing against the other end of the vanes of each set for effecting said sliding movement of the latter.
